The ornamental design for a case for a game cartridge or compact disk, as shown and described.

DESCRIPTION

FIG. 1 is a perspective view of a case for a game cartridge or compact disk, with its two panels pivoted open, showing my new design;

FIG. 2 is an enlarged front elevational view thereof shown in a closed position;

FIG. 3 is a right side elevational view of FIG. 2;

FIG. 4 is a left side elevational view of FIG. 2;

FIG. 5 is a top plan view of FIG. 2, the bottom plan view being a mirror image thereof;

FIG. 6 is a rear elevational view of FIG. 2; and,

FIG. 7 is an enlarged front elevational view of FIG. 1.

FIG. 1

FIG. 2

FIG. 3

FIG. 4

FIG. 5

FIG. 6

FIG. 7
